UNITED STATES PATENT OFFICE.

BYRON L. MOORE, OF BUFFALO, NEW YORK.

KEY-SWITCH.

1,341,719.

Specification of Letters Patent.

Patented June 1, 1920.

Application filed August 24, 1918. Serial No. 251,213.

To all whom it may concern:

Be it known that I, BYRON L. MOORE, a citizen of the United States of America, and a resident of the city of Buffalo, county 5 of Erie, and State of New York, have invented certain new and useful Key-Switches, of which the following is a full, clear, and exact description.

My invention relates generally to key switches, which are used in telephone, radio telephone, and radio telegraph systems, sometimes referred to as anti-capacity keys. It will be understood by those skilled in the art, that previous forms of similar apparatus have been detrimental, in that they have been constructed with flat springs insulated from each other but facing each other in close proximity and, therefore, having considerable electrostatic capacity. Due 10 to this fact, these keys, when the springs thereof were in or out of mechanical contact with each other, have permitted the passage of a perceptible amount of induced alternating current. It has, therefore, been 15 difficult to entirely interrupt alternating currents, particularly those of high-frequency with these previous forms of keys; it being well known that two flat metal surfaces facing each other in close proximity 20 separated by a dielectric—such as air or an insulating compound—act as a condenser with considerable apparent conductivity to alternating currents of high-frequency.

The general object of my invention has 25 been to provide a key or switch which shall overcome defects inherent in the keys of previous construction, with respect to the capacity effects just described.

Another object has been to provide a 30 mounting for the master springs, which shall furnish air spaces around the springs for the purpose of reducing the electrostatic capacity.

Another object has been to provide a key 35 of this nature which shall be of simple and rugged construction, and one cheap to manufacture.

The above objects and advantages have 40 been accomplished by the device shown in 50 the accompanying drawings, of which:

Figure 1 is a side elevation of the complete device; a portion thereof being shown in section.

Fig. 2 is a sectional elevation thereof, 5 taken on line 2—2 of Fig. 1.

Fig. 3 is a sectional, plan view, taken on line 3—3 of Fig. 1.

Fig. 4 is a side elevation of one of the master springs.

Fig. 5 shows a modified form of master 60 spring.

Fig. 6 shows another form of master spring.

My switch comprises an insulating block 5, which carries the contact springs of the 65 device. This block is carried by a frame 6, preferably U-shape and having its ends 7 and 8 fastened to the block, 5. This frame may be made either of metal or insulating material. Carried by the top of 70 the frame 6 is a cam actuating mechanism of the well known type, and preferably comprising a lever 10, a cam 11, and cam rollers 12 of insulating material, there being a roller disposed on each side of the cam 11. 75

Carried by the insulating block 5 are a plurality of directly actuated or master springs 13. These springs are each formed with a reduced lower portion 25, thereby providing shoulders 26. This reduced portion of each spring is pressed into an aperture 27 (slightly smaller than the width of the portion) formed in the block 5. The spring is forced down until the shoulders 26 contact with the upper face of the block, 85 whereby the spring is securely held against rotation and the air spaces 28 are provided. The upper end 29 of each spring is bent inwardly toward the center of the key and then outwardly, or otherwise formed so as to 90 be mechanically engaged by the rollers 12 and be actuated thereby. The upper end 29 of each of the master springs is so angularly arranged that when the cam actuating mechanism is operated, the rollers will be locked 95 in position until manually released.

Disposed opposite and facing each of these master springs 13, and of different electrical polarity or potential, are one or more anvil springs 14. These springs are also secured 100 near their lower ends within the insulated block 5, and have their upper ends extending to near the top of the master springs 13. The portion of the spring which engages with the block may be knurled or roughened, but is 105 preferably provided with projecting tabs 30, which prevent the spring from rotating. The anvil springs 14 are preferably cylindrical in shape and each has its upper end portion bent inwardly so as to bring the end 110

thereof in close proximity to the master spring, at the same time keeping the greater part of the spring as distant as possible from the master spring, within the limits of the 5 construction. This construction affords a small area of opposing surface and at the same time maintains a substantial distance between the springs referred to. As the result of this construction, my key has the 10 advantages of low electric capacity, mechanical rigidity of the anvil spring, and permits the adaptation of the spring end to contact uses.

While I have shown and described the 15 anvil springs of round cross-section, they may, if desired, be of any other suitable cross-section, as diamond-shape or square-shape.

In Fig. 5, I show a modified form of master spring. In this figure, the upper end 9 of the spring 21, which contacts with the cam actuating mechanism, is provided with a return bend 22 arranged in interspaced relation. This construction provides means 25 for dampening the vibration of the master spring when suddenly operated or released.

In Fig. 6, I show another form of spring end 23 for accomplishing the same purpose as the form shown in Fig. 5. In this form, 30 a piece of spring metal 20 is riveted to the upper end of the master spring 24.

The master springs, instead of being formed of flat material, as shown, may be made of any other desirable cross-section, 35 such as round, square, or diamond-shaped wire and may have their upper ends formed in any desired manner.

It will be clear that when the cam lever is operated, the rollers 12 will contact with 40 the upper bent ends of the master springs and move these springs into or out of electrical contact with the anvil springs.

It is obvious that while, for purposes of illustration, I have shown my key provided 45 with a certain number of springs, it may contain any other number and arrangement of springs to adapt it for use in connection with different electrical circuits; the lower ends of the springs being, of course, connected in the well known manner with the 50 circuits being controlled.

It is also evident that the frame supporting the mechanical parts may take any desired form or be constructed of a single

piece of material, as shown, or a plurality of 55 parts, and be constructed of any desirable material or materials.

Having thus described my invention, what I claim is:

1. In a key switch, the combination, with 60 a frame and a cam actuating mechanism carried by the frame, of a block of insulating material carried by the frame, master springs fastened near their lower ends within the block and having their upper ends bent 65 so as to be mechanically engaged by the cam actuating mechanism and be actuated thereby, anvil springs, each having the surface adjacent the master spring of small, superficial area as compared to the area of the 70 master spring, said anvil springs being secured near their lower ends within the block, the upper ends of the anvil springs being bent toward the adjacent master springs so as to bring the upper end in close proximity 75 thereto.

2. In a key switch, the combination, with 80 a frame and a cam actuating mechanism carried by the frame, of a block of insulating material carried by the frame, master springs fastened near their lower ends within the block and having their upper ends bent so as to be mechanically engaged by the cam actuating mechanism and be actuated thereby, anvil springs, cylindrical in cross 85 section and secured near their lower ends within the block, the upper ends of the anvil springs being bent toward the adjacent master springs so as to bring the upper end in close proximity thereto. 90

3. In a key switch, the combination, with 95 a U-shaped frame and a cam actuating mechanism carried by the frame, of a block of insulating material carried at the lower end of the frame, master springs fastened 100 near their lower ends within the block and having their upper ends bent so as to be mechanically engaged by the cam actuating mechanism and be actuated thereby, anvil springs substantially cylindrical in cross- 105 section and secured near their lower ends within the block, the upper ends of the anvil springs being bent toward the adjacent master spring so as to bring the upper ends in close proximity thereto. 105

In testimony whereof I have hereunto signed my name.

BYRON L. MOORE.
